UNITED STATES PATENT OFFICE.

HERBERT ETHERIDGE, OF LONDON, ENGLAND, ASSIGNOR TO THE BAR-LOCK TYPE-WRITER COMPANY LIMITED, OF LONDON, ENGLAND.

TYPE-BAR ACTION.

1,212,921.

Specification of Letters Patent.

Patented Jan. 16, 1917.

Application filed March 22, 1916. Serial No. 85,806.

To all whom it may concern:

Be it known that I, HERBERT ETHERIDGE, a subject of the King of England, residing at Ealing, London, W., England, have invented certain new and useful Improvements in Type-Bar Actions, of which the following is a specification.

This invention relates to type-bar actions and has for its object to provide a durable form of type-bar mechanism which will give acceleration of the type-bar throughout the whole of the downward movement of the key if necessary.

One feature of the invention consists in providing the keys with a projecting tongue which carries the means for operatively connecting it to the sub-lever, which tongue enables the interconnecting means to be applied at different distances from the key according to the position in which the key is set in the machine.

In the accompanying drawings which illustrate one method of carrying out this invention:—Figure 1 is a side elevation of the type-bar mechanism in the position of rest, and Fig. 2 is a side elevation of the same shown on a smaller scale and with the parts in the striking position.

The same letters indicate the same parts in both figures.

The frame shown in section at A may be a segmental member such as is commonly employed to carry the type-bars of a typewriter, and the type-bars B are pivoted thereto at B¹ and assume an approximately horizontal position when at rest. Each type-bar has a short operating arm B² which is connected by a link C to the free end of a sub-lever D. The sub-lever is approximately vertical when in the position of rest and is pivoted at its lower end at D¹.

Each sub-lever is provided with a key-lever E for operating it. The key-lever is pivoted at E¹ at a point behind and above the point D¹ about which the sub-lever is pivoted. The key-lever has a lateral tongue or depending portion E² which carries a roller E³. The roller is secured by a large headed screw or rivet E⁴ the head of which provides a shoulder to keep the sub-lever D laterally in place against the pendent portion E² of the key-lever E. The sub-lever is slotted at D², the upper end of the slot D³ being made sufficiently large to allow the head of the rivet which carries the roller E³

to pass freely through it, but the part D² of the slot is narrower, so that once the roller and its headed rivet are in position, the parts cannot be disconnected without bringing the rivet and its roller back to the enlarged portion D³. It will be seen that the sub-lever is approximately perpendicular to the key-lever as the latter is in the horizontal position when at rest, and the sub-lever, as has already been stated, is approximately vertical, and across the angle formed between these two members a spring F is stretched, one end being connected to the sub-lever and the other end to the key-lever, so that the tendency of the spring is to always keep the key-lever raised and the sub-lever pulled forward to the limit of its movement, that is, to the vertical position. It should also be observed that the spring F always keeps the roller E³ in contact with the working face of the slot D² so that back-lash is avoided.

The operation of this mechanism is as follows:—When the key-lever is depressed, the roller E³ is made to travel along the curved path indicated by the chain line X—X. The chain-line passes through the point where the roller E³ is in contact with the rear side of the slot D² of the sub-lever, and it will be seen that from this point downward, the line X—X makes an acute angle with the line or path upon which the said rear face lies, this angle widening out on the side which is toward the pivot-point D¹. It follows therefore that as the roller, which may be considered the part of the key-lever E which is in engagement with the sub-lever D rolls down the said rear side of the slot D² and moves rearwardly along the path X—X, the sub-lever D will be forced back, and further, as the roller approaches the pivot-point D¹ of the sub-lever, the angle between the path X—X and the line upon which the rear face of the slot D² lies will be increased. This means that, as the key-lever is pressed down with an even movement, the sub-lever will be pushed back with an accelerated movement due partly to the changing angle which the rear face of the slot D² makes with the path X—X and partly to the fact that the roller E³ is all the time getting closer to the pivot-point D¹ of the sub-lever. The movement of the sub-lever of course raises the type-bar by means of the link C, and the type-bar when

it strikes the platen is approximately vertical as shown in Fig. 2 and the other parts assume the different positions shown in that figure. Owing to the accelerated movement 5 the type-bar completes its stroke with a sharp action, which gives a clear impression and what is commonly known as a light action is obtained because so little effort is required to move the parts at the commencement 10 of the downward movement of the key-lever. The depression of the key-lever and the throwing back of the sub-lever stretches the spring F so that as soon as the key-lever is released the said spring draws 15 the parts back again to the position shown in Fig. 1.

Obviously the degree of acceleration may be varied as required by varying the angle of the slot D² relatively to the path X—X. 20 In the case shown in the drawings, the slot D² is radial to the point of pivoting D¹ of the sub-lever. It will be readily seen that if the slot D² were so directed that the rear face which constitutes the driving-face was 25 set on a line which would pass to the forward side of the center of the pivot-point D¹, the degree of acceleration would be increased.

The mounting of the roller E³ upon a 30 pending tongue secured to the key-lever E is a feature of importance, as in addition to enabling the parts to be arranged to give the accelerated movement already mentioned, it constitutes a convenient means of 35 adjustment in manufacture.

It will be appreciated that the sub-levers require to be of varying length according 40 to the position of the type-bar on the segmental arc which any particular sub-lever is to operate, and this necessitates that the pin and slot connection, that is, the roller E² and slot D², also need to be adjusted, so that the shorter and longer levers shall 45 all give the requisite movement to their respective type-bars, the degree of depression for each key-lever being maintained the same throughout. With the arrangement shown, the key-levers E can all be stamped out as multiples one of the other, the tongue 50 E² being left long enough for the longest tongue required. This saves multiplicity of tools in the production of the parts. All that is then necessary is to drill a hole for the interconnecting stud or the pin which 55 carries the roller E³ at different heights in the different keys for the purpose of the adjustment already referred to. The sub-levers also can all be stamped out to one length and then shortened at the end which 60 receives the link C, the shortening being done at the same time as the hole is punched for pivoting the link C to the lever. This

feature of the invention is independent of whether the slot D² is arranged to accelerate the type-bar throughout the whole of the 65 stroke or not, but has been invented as the most convenient means for giving the desired continuous acceleration.

What I claim as my invention and desire to secure by Letters Patent is:—

70

1. In type-bar mechanism for a typewriter, the combination of, a type-bar, a pivoted sub-lever operatively connected therewith, a key-lever situated approximately at right-angles to the sub-lever and 75 having a tongue which lies approximately parallel with the sub-lever, a projection secured to the tongue and having sliding engagement with a driving-face on the sub-lever, the arrangement of the parts being 80 such that the said projection travels in a path which is toward the point of pivoting of the sub-lever but inclined also to one side of the same in the direction in which the sub-lever is to be moved whereby the 85 sub-lever is swung about its pivot with an accelerated movement which may be made to continue throughout the whole of the stroke and the tongue allows the projection to be situated at different points along its 90 length, substantially as and for the purpose set forth.

2. In type-bar mechanism for a typewriter, the combination of, a type-bar, a pivoted sub-lever in the form of a plain arm 95 so that it can be shortened as required, said sub-lever being operatively connected with the type-bar and having a slot radial to its pivot, a key-lever situated approximately at right-angles to the sub-lever and having a 100 tongue which lies approximately parallel with and at the side of the sub-lever, a projection secured to the tongue and engaging the slot in the sub-lever, the arrangement of the parts being such that the said projection travels in a path which is toward the point of pivoting of the sub-lever but inclines also to one side of the same in the direction in which the sub-lever is to be moved whereby the sub-lever is swing about its 105 pivot with an accelerated movement which may be made to continue throughout the whole of the stroke and the tongue allows the projection to be situated at different points along its length, substantially as and 110 for the purpose set forth.
